UNITED STATES PATENT OFFICE

172,941

TOY ROBOT

Thomas H. Wood, Jr., Cincinnati, Ohio, assignor
of ten per cent to Betty Wood, Norwood, Ohio

Application April 6, 1954, Serial No. 29,887

Term of patent 3½ years

(Cl. D34—4)

To all whom it may concern:

Be it known that I, Thomas H. Wood, Jr., a citizen of the United States, residing at Cincinnati, in the county of Hamilton and State of Ohio, have invented a new, original, and ornamental Design for a Toy Robot, of which the following is a specification, reference being had to the accompanying drawing, forming part thereof.

Figure 1 is a front elevational view of a toy robot, showing my new design;

Figure 2 is a rear elevational view thereof;

Figure 3 is a side elevational view of the same;
and

Figure 4 is a top plan view of the toy robot.

I claim:

The ornamental design for a toy robot, as shown.
